US0D1058297S

(12) **United States Design Patent** (10) **Patent No.:** **US D1,058,297 S**
Wadsworth et al. (45) **Date of Patent:** **** Jan. 21, 2025**

(54) **CONTAINER SPOUT**

(71) Applicant: **Hydrojug, Inc.**, Ogden, UT (US)

(72) Inventors: **Hayden Wadsworth**, Ogden, UT (US);
Ethan Powell, Salt Lake City, UT (US)

(73) Assignee: **HYDROJUG, INC.**, Ogden, UT (US)

(**) Term: **15 Years**

(21) Appl. No.: **29/896,987**

(22) Filed: **Jul. 10, 2023**

(51) **LOC (15) Cl.** **07-01**

(52) **U.S. Cl.**

USPC **D7/396.2**

(57) **CLAIM**

The ornamental design for a container spout as shown and described.

DESCRIPTION

FIG. 1 is a first perspective view of the container spout design;

FIG. 2 is a second perspective view thereof;

FIG. 3 is a first side view thereof;

FIG. 4 is a second side view thereof;

FIG. 5 is a front view thereof;

FIG. 6 is a back side thereof;

FIG. 7 is a top view thereof;

FIG. 8 is a bottom view thereof;

FIG. 9 is a first perspective thereof in a container lid environment; and,

FIG. 10 is a second perspective thereof in a container lid environment in an alternate position of use.

The dashed lines depict portions of the container spout that form no part of the claimed design.

1 Claim, 10 Drawing Sheets
